UNITED STATES PATENT OFFICE

JAMES W. FITZGERALD, OF MAYSVILLE, KENTUCKY.

STALLION-SHIELD.

SPECIFICATION forming part of Letters Patent No. 508,100, dated November 7, 1893.

Application filed November 16, 1891. Serial No. 412,105. (No model.)

To all whom it may concern:

Be it known that I, JAMES W. FITZGERALD, a citizen of the United States, residing at Maysville, in the county of Mason and State 5 of Kentucky, have invented certain new and useful Improvements in Stallion-Shields; and I do declare the following to be a full, clear, and exact description of the invention, such as will enable others skilled in the art to which 10 it appertains to make and use the same.

My invention relates to improvements in stallion shields, and it consists of a shield comprising a belly piece, a second piece composed of a strip of leather or cloth carrying 15 blunt staples and pricking points, a strip of sole leather backing said strip, a strip of steel backing the sole leather and a covering for the steel strip; the whole forming a light, durable, and effective device and one not liable 20 to get dirty and breed disease.

In the accompanying drawings Figure 1 is a view of a horse with my improved shield applied. Fig. 2 is a cross sectional view of the shield, and Fig. 3 is a side view of the shield 25 removed from the harness or attaching device.

In carrying out my invention I take a piece of rubber, leather or other suitable material of a sufficient length and width to be placed under the belly of a horse as indicated at A, 30 and arm or provide the same with staples a, having blunt ends which project a sufficient distance from the under side of said strip. I then secure upon this strip A against the connecting branches of the staple a strip B, composed of sole leather or the like, after which 35 I secure upon the outer side a strip C, of steel or similar material and then cover the whole with a strip of leather D. These various pieces of material may be connected by stitches 40 or otherwise and the steel strip C should be curved or bowed to conform to the natural curvature or shape of a horse's belly as better shown in Fig. 2 of the drawings.

E, indicates a strip which is attached at opposite ends to the opposite ends of the shield 45

as shown at b, and is of less length than said shield so as to retain the latter in the bowed position illustrated.

Arranged at various points throughout the bed of blunt ends of staple a, are sharp pointed 50 staples d, which are of greater length than said blunt staple for a purpose which will be presently described and the longitudinal edges of the parts comprising the shield may be protected and secured together by binding 55 strips e.

F, indicates loops at opposite ends of the shield which are designed to receive the supporting or attaching straps as will be presently explained.

G, indicates a ring, there being one at each end of the shield in the loops F, thereof and from these rings pass straps H, which extend up to and are attached to a back strap I, which back strap has its forward end in turn 65 secured to a collar K, which is also preferably composed of a suitable strap and buckle. The collar K, is connected with the rings on opposite sides of the horse by means of side straps L, and the various straps carry buckles 70 whereby they may be rendered adjustable.

The harness above described for attaching the shield to the horse's body, is preferable, but it is obvious that inasmuch as said harness forms no part of my present invention, 75 any other approved harness might be employed for the purpose.

Having described my invention, what I claim is—

A stallion shield comprising a belly piece 80 and a second piece composed of a strip of leather or cloth carrying blunt staples and pricking points, a strip of sole leather backing said strip, a strip of steel backing the sole leather, and a covering for the steel 85 strip, substantially as specified.
